UNITED STATES PATENT OFFICE.

LLOYD LOGAN, OF PITTSBURGH, PENNSYLVANIA.

MEANS FOR CONTROLLING A PRODUCTION PROCESS.

Application filed December 20, 1920. Serial No. 432,086.

To all whom it may concern:

Be it known that I, LLOYD LOGAN, a citizen of the United States, and resident of Pittsburgh, county of Allegheny, State of Pennsylvania, have invented an Improvement 5 in Means for Controlling Production Processes, of which the following description, in connection with the accompanying drawing, is a specification, like characters 10 on the drawing representing like parts.

This invention relates to means for automatically controlling various operations and it has particular reference to a controlling means which is rendered operative by or 15 through the use of radiant energy.

The invention is capable of a wide range 20 of use and may be arranged to exercise a control over an operation or process by limiting the amount of production, or by stopping or starting machinery, or by varying the 25 character of the operation or process as circumstances vary, or by operating alarm or indicating devices, or in fact by accomplishing a large variety of other operations which affect in some way the operation or process in question.

In carrying out my invention I provide means whereby the carrying out of the operation will cause a variation in radiant energy, preferably radiant energy in the form 30 of light, and I also provide means responsive to such variations in the radiant energy to exercise the desired control over the operation.

In order to give an understanding of my invention I have illustrated in the drawings in a more or less diagrammatic way several devices embodying the invention and by 35 which different processes can be controlled in different ways.

Fig. 1 illustrates my invention as it might be applied to exercising a control over the number of rotations of a shaft or other given part so as to stop the shaft from rotating when the desired number of rotations 45 have been completed.

Fig. 2 illustrates my invention as it might be applied to exercise control over the liquid level in a tank in which liquid is being delivered and from which it is being withdrawn.

Fig. 3 is a plan view of the device shown in Fig. 2.

Fig. 4 is a diagrammatic view showing 55 my invention as it might be embodied in an apparatus for effecting fine measurements

by comparison of light waves through the production of interference fringes. In these drawings, it is to be understood that the light-proof cases over the optical parts are 60 omitted for the sake of clearness. Figs. 5 and 6 are views showing different embodiments of the invention.

In all the above embodiments of the invention the radiant energy which is used is 65 light energy but I wish to state that the invention is not limited to constructions in which the radiant energy is in the form of light, as radiant energy in other forms may be used without departing from the invention. 70

The apparatus shown in Fig. 1 is designed to exercise a control of some sort over a rotating element such, for instance as a shaft. This element is indicated at 1 and it may be 75 any rotated part. In providing an arrangement for exercising control over the rotations of a rotary element I provide means whereby the rotation of such element will cause variations in radiant energy and also 80 provide a receiving element responsive to such variations which operates to exercise the desired control. In the apparatus shown in Fig. 1 the radiant energy is light emitted from a source of light 2 and the receiver 85 which is responsive to variations in light is a light-sensitive cell 3, such as a selenium cell. The variations in light energy may be produced by rotation of the element 1 in various ways without departing from my 90 invention. Merely as an illustration I have shown the element 1 as provided with a transverse opening 4 so situated that as the element rotates the opening will at each one-half rotation be brought in line with the 95 light 2 so that a ray of light will be projected through the aperture. The light-sensitive cell is situated so that the ray of light which passes through the aperture 4 will be received thereby and with this arrangement 100 the cell will be subjected to a light impulse twice during each rotation of the element 1. This light sensitive cell is connected in a circuit 5 having a battery or other source of electrical energy 6 therein and the circuit 105 connects to a relay 7. The light sensitive cell 3 is of such a character that the electrical resistance thereof varies as the amount of light to which the cell is subjected varies and with this arrangement therefore there 110 will be variations in the resistance in the circuit 5 corresponding to the rotations of the

110

element 1. If the cell 3 is a selenium cell then the resistance in the circuit 5 will decrease when the light ray is projected onto the cell through the opening 4 and will increase whenever the shaft is turned so as to cut off the light from the cell. At each one-half rotation of the element 1 therefore the resistance in the circuit 5 will be momentarily diminished.

10 The relay 7 is arranged to close a second circuit 8 having a source of electricity 9 therein which is considerably greater than that in the circuit 5. This relay is constructed so that the resistance of the light-sensitive cell when the latter is not subjected to the light ray will be sufficient to prevent the relay from operating but when the selenium cell is subjected to the light ray projected through the aperture 4 then 15 the resistance of the circuit 5 will be diminished sufficiently so that the relay will become operative to close the circuit 8. This circuit is shown as connected to a counting mechanism 10 which may have 20 any suitable or usual construction and which is arranged so that each time the circuit 8 is closed the counting mechanism will be stepped forward one step. This counting mechanism therefore will count the 25 number of times that the circuit 8 is closed and this in turn depends upon the number of times the element 1 is rotated.

The use of a projection on the shaft to obstruct the light impinging on the light-sensitive cell once during each revolution 30 is another modification within the scope of the invention. It is intended to apply the device in a similar manner to reciprocating parts.

40 The counting mechanism may be arranged to control some suitable devices, such, for instance, as a motor or driving mechanism which in turn controls the motion of the element 1 or of any element 45 whose motion depends on that of element 1. Merely as an illustration I have shown a counting mechanism arranged so that after it has counted a certain predetermined number it will close a control circuit 11 which 50 in turn operates a solenoid or magnet 12 that controls a stopping mechanism or any other device which will stop or affect in some way the rotation of the element 1.

With an arrangement of this sort therefore 55 it would be possible to employ a counting mechanism which would become operative to open an operating circuit or perform some other act which would have the effect of bringing the element 1 to rest after 60 it has made a predetermined number of revolutions.

In Figs. 2 and 3 I have illustrated another application of my invention by which it is used to exercise a control over the liquid level in a tank.

In this embodiment the tank is indicated at 13 and it is provided with an inlet pipe 14 and with a discharge pipe 15 from which the contents may be withdrawn. The inlet pipe 14 is shown as having a valve 16 there-⁷⁰ in.

17 indicates a hollow transparent prism which is connected to the tank 13 by the two pipe connections 18 and 19, said prism being arranged at substantially the desired liquid level in the tank. With this arrangement when the liquid level in the tank reaches the desired height the prism will be filled with liquid and when the liquid level falls below this height the prism will be emptied of liquid.

20 indicates a source of light arranged to direct a beam onto the prism and 21 is a light sensitive cell connected in a circuit 22 having a relay 23 therein. This relay in turn controls an operating circuit 24 which has therein a solenoid or magnet 25 that controls the valve 16.

The arrangement of the source of light and the selenium cell and the prism is such that so long as there is no liquid in the prism the light rays will pass through the prism but when the prism is filled with liquid the beam of light from the source of light 20 will be deflected by the prism, due to total reflection onto the light sensitive cell 21, thus reducing the resistance of the circuit 22 and causing the relay 23 to operate to close the circuit 24.

When this occurs the solenoid or magnet 25 will be energized thereby closing the valve 16 and preventing further delivery of liquid into the tank.

When the liquid level in the tank falls below the prism so that the latter is emptied of liquid then the light will be withdrawn from the light sensitive cell and the relay will become inoperative thus allowing the valve 16 to open again automatically.

In this embodiment of the invention the radiant energy deflected by the prism 17 is made use of to exercise control over the liquid level in the tank.

In Fig. 4 I have illustrated diagrammatically still another embodiment of my invention which involves the use of a so-called interferometer by which interference fringes may be produced. The type of interferometer shown involves a source of light 26 and a glass plate 27 which is thinly coated on one side with silver and is arranged to receive the beam of light 28 at an angle of 45 degrees. The thickness of the coating of silver is such that one-half of the light is reflected as shown at the dotted line 29 and one-half is refracted along the line 30. 31 and 32 are two mirrors or other reflectors one of which is situated at right angles to the reflected beam of light 29 and the other of which is sit-

uated at right angles to the refracted beam 30. The mirror 31 reflects the reflected light 29 back onto the silvered plate 27 and the mirror 32 reflects the refracted beam 30 back also onto the plate 27, both beams retracing their paths. This plate 27 acts to reflect a portion of the light reflected from the mirror 32 as shown at 33 and a portion of the light reflected by the mirror 31 is refracted by the plate 27 so that both this refracted light and reflected light form a single beam indicated at 33. 34 is a screen receiving this beam and is provided with a slit 35. Assuming that the beam of light 28 is of one color, for instance a red color and that the mirrors 31 and 32 are exactly the same distance from the glass plate 27 then the light waves of the two beams 33 will be in phase and each will 20 augment the other; but if the mirror 31 for instance is a greater distance from the glass plate 27 then the mirror 32 by an amount equal to one-half the wave length of the red light wave then the waves of the 25 two beams at 33 will be in opposite phase and will neutralize each other thus producing total extinction of light due to the interference of the light waves. Again if the mirror 31 is given a still further movement 30 so that its distance from plate 27 is greater than that of the mirror 32 by an amount equal to one, two, three or any number of wave lengths of the red light rays, then the waves of the two beams will be in phase 35 again at the screen and light will exist at this point.

Hence if it be assumed that the mirror 32 is stationary and the mirror 31 is gradually moved away from the plate 27 alternate light and darkness will be produced at the slit 35, the change from light to darkness representing a movement of the mirror 31 equal to one-half of the length of a wave of red light. The red light wave 40 length is about 1/30,000 of an inch and therefore with such an apparatus using red light each movement of the mirror 31 through 1/60,000 of an inch will produce a change from darkness to light or light to 45 darkness at the slit 35.

In using an apparatus of this type for carrying out my invention I would place a light sensitive cell 36 adjacent the slit 35 to receive light there through, said slit being connected in a circuit 37 having a relay 38 therein adapted to close an operating circuit 39. This operating circuit may be arranged to actuate any desired apparatus for exercising the desired control. 50 One such apparatus would be a counting mechanism 40 which is actuated by successive impulses in the circuit 39 and the counting mechanism could be arranged to close the circuit 41 having some control 55 device therein which becomes operative 60

when a certain number of impulses has been counted.

A device of this sort may be used for various purposes, if for instance it is desired to make a very accurate measurement 70 of some object such as the object 42. In this case a microscope 43 might be mounted on the mirror 31 and the latter positioned so that the cross hairs of the microscope would be focussed on one end of the object 75 42. The counting mechanism would then be connected into the circuit and the mirror moved by means of a screw 44 or any other suitable device so that the cross hairs of the microscope would be focussed on the 80 opposite end of the object 42. Such movement of the mirror would produce alternate light and darkness at the slit 35 resulting in subjecting the cell to alternate light and darkness and this would operate 85 as above described to actuate the counting mechanism. The number of impulses given to the counting mechanism by the movement of the microscope from one end of the object 42 to the other would give the 90 dimension of the object 42 in wave lengths of the particular light being used. Supposing for illustration that the indicator indicated 10,000 wave lengths and if the light being used is a red light of 0.00082 95 millimetres wave length these 10,000 wave lengths would indicate a dimension of 0.82 centimeters.

Another way of using this device would be for the purpose of securing accurate dimensions in a piece of optical glass or other material being polished or operated upon in some machine. For instance if a piece of glass, such as an interferometer plate is 100 being ground by a machine to secure very accurate dimensions, then the mirror 31 or a projection extending therefrom might be arranged to make contact with such piece at intervals, at the same time automatically arresting the motion of the machine. In 105 this case the counting mechanism could be arranged to close the circuit containing the control mechanism when the desired dimension is approached thus stopping the operation 110 of the machine or operating an alarm. 115

When the material being worked on has the required reflecting properties suitable provisions may be made to use such a part in a similar manner to the mirror 31, the reduction in thickness of this part producing the same movement of interference fringes over slit 35 as produced by the movement of the mirror 31 by screw 44. When the desired dimension is reached the counting device may be made to close a circuit to stop the operation.

While I have above described several applications of my invention yet I wish to state that these are merely illustrations of 120 different uses to which the invention may be 125 130

put and that they are not intended in any way as setting up limitations for the invention.

I claim:

- 5 1. The combination with means for producing radiant energy, of other means to cause variations therein by the quantity produced in a process or operation in which material is acted upon, and means rendered 10 operative by said variations to exercise control over said process or operation.
- 15 2. The combination with means for producing radiant energy, of other means to cause variations therein by the quantity produced in a process in which a material 20 is acted upon and which is independent of the means for producing said radiant energy, and means rendered operative by said variations when a predetermined quantity has been produced to exercise control over the process.
- 25 3. The combination with means for producing radiant energy, of other means to cause variations therein by the quantity produced in a production process which is independent of said means for producing

radiant energy, and means responsive to such variations to give a measurement of production.

4. The combination with means for producing radiant energy, of other means to cause variations therein by the quantity produced in a process in which material is acted upon and which is independent of said means for producing radiant energy, 35 and means responsive to said variations in radiant energy to perform a predetermined function.

5. In a device of the class described, the combination with means for producing 40 radiant energy, of other means to cause variations therein by variations in quantity or amount involved in a process in which material is being acted upon, which is independent of the means for producing radiant 45 energy, of an element controlled by said variations in radiant energy and adapted to respond in a predetermined degree to such variations in quantity or amount.

In testimony whereof, I have signed my 50 name to this specification.

LLOYD LOGAN.
